UNITED STATES PATENT OFFICE.

HERBERT O. RUSSELL, OF DETROIT, MICHIGAN, AND CHARLES LEIGH PAULUS, OF DAYTON, OHIO.

MOUNT FOR FLEXIBLE SYNCHRONIZED GUNS.

Application filed April 18, 1922. Serial No. 555,422.

To all whom it may concern:

Be it known that we, HERBERT O. RUSSELL and CHARLES LEIGH PAULUS, citizens of the United States, residing, respectively, at 5 Detroit and Dayton, in the counties of Wayne and Montgomery and States of Michigan and Ohio, have invented certain new and useful Improvements in Mounts for Flexible Synchronized Guns, of which 10 the following is a specification.

This invention relates to mounts for flexible synchronized guns, the object of the present invention being to produce a gun mount which will admit of the gun being 15 adjusted in azimuth, at the same time maintaining the operation of the gun in synchronization with the propeller.

With the above and other objects in view, the invention consists in the novel construction, combination and arrangement herein 20 fully described, illustrated and claimed.

In the accompanying drawings:

Figure 1 is a top plan view, partly in section, of our device;

Figure 2 is a side elevation of our device with certain portions shown in dotted lines.

Referring to the drawings, the trunnions 1 of the gun 1' are supported by a turntable 2 mounted for rotation in suitable 30 bearings provided on a stationary base 3. Mounted in the base is a diametrically slideable bar 4 which is hollow to receive the end portion of an impulse cable 5 leading to the stationary impulse generator.

A bell crank lever 6 is mounted on a horizontal pivot 7 on bearing members 8 carried by the bar 4, and has one arm attached to the cable 5 and its other arm swivelled, with slight play at 9 to the lower end of a 40 vertical movable connecting rod 10 mounted for vertical reciprocatory movement directly in line with the axis of movement of the turntable 3.

A second bell crank lever 11 is mounted on 45 a horizontal pivot 12 on the turntable and has one arm swivelled to the upper end of the connecting rod 10. The other arm of the lever 11 is attached to one end of a trigger

motor operating cable 13 which extends to the trigger motor 13' mounted on the side 50 of the gun. A long cam surface 14 on the turntable works in contact with a roller 15 mounted on a vertical stud or shaft 16 adjacent to and on one end of the slideable bar 4.

Owing to the center location of the rod 10, 55 when the gun is swung to the right or to the left, impulses will be transmitted from the cable 5 to the cable 13 through the medium of the bell crank levers 6 and 11 and the connecting rod 10 regardless of the portion 60 armed by the gun.

As the turntable supporting the gun turns in its bearings, the cam 14 forces the roller outwardly and thus imparts a thrust to the bar 4. The result of this motion will be 65 a shifting of the pivot of the bell crank lever 6. This in turn effects an adjustment of the impulse cable 5 and causes the firing impulses to come at a lower point on the impulse cam of the generator. Due to the 70 play in the swivel 9, the pivot of the bell crank lever 6 may approach the rod 10 or recede therefrom without altering in any way the vertical thrust of the connecting rod 10 or interfering with its movement. A 75 clamping member 17 is provided for use in securing the turntable at any desired adjusted position of the gun.

What we claim is:

1. A mount for a flexible synchronizing 80 gun, embodying a stationary base, a turntable on said base between said gun and its impulse generator, a gun having trunnions in bearings on said turntable, a trigger motor on the gun, and means for operating said 85 trigger motor from a stationary impulse generator while permitting rotation of the turntable, said means comprising an impulse cable, a trigger motor operating cable, and connecting means between said cable including a connecting rod the longitudinal axis of 90 which is coincident with the axis of rotation of the turntable.

2. A mount for a flexible synchronizing 95 gun, embodying a stationary base, a turntable on said base between said gun and its

impulse generator, a gun having trunnions in bearings on said turntable, a trigger motor on the gun, and means for operating said trigger motor from a stationary impulse generator while permitting rotation of the turntable, said means comprising an impulse cable, a trigger motor operating cable, and connecting means between said cable includ-

ing a connecting rod the longitudinal axis of which is coincident with the axis of rotation of the turntable, and levers connecting said cables with said connecting rod. 10
In testimony whereof we affix our signatures.

HERBERT O. RUSSELL.
CHARLES LEIGH PAULUS.
